[57] CLAIM

[21] Appl. No.: 447,879

The ornamental design for a propeller guard for boat motor, as shown and described.

[22] Filed: Dec. 7, 1989

DESCRIPTION

[52] U.S. Cl. D15/4; 440/72

FIG. 1 is a perspective view of a propeller guard for

[58] Field of Search D12/70; D15/4, 5;

FIG. 2 is a side elevational view;

440/71-72, 107, 67; 416/247 A

FIG. 3 is a top plan view;

FIG. 4 is a front elevational view;

FIG. 5 is a rear elevational view; and

FIG. 6 is a bottom plan view.

The broken line showing of an outboard motor and boat

hull in FIG. 1 is for illustrative purposes only and forms

no part of the claimed design.
